(57) **CLAIM**

The ornamental design for a mattress cover assembly, as shown and described.

DESCRIPTION

FIG. 1 is a front elevational view of a mattress cover assembly of the present invention in accordance with another alternative embodiment of the mattress cover assembly;

FIG. 2 is a rear elevational view of the mattress cover assembly of FIG. 1;

FIG. 3 is a left side elevational view of the mattress cover assembly of FIG. 1;

FIG. 4 is a right side elevational view of the mattress cover assembly of FIG. 1;

FIG. 5 is a top view of the mattress cover assembly of FIG. 1;

FIG. 6 is a bottom view of the mattress cover assembly of FIG. 1;

FIG. 7 is a perspective view of the mattress cover assembly of FIG. 1;

FIG. 8 is another perspective view of the mattress cover assembly of FIG. 1, showing a top cover of the mattress cover assembly detached from a bottom cover of the mattress cover assembly; and,

FIG. 9 is a perspective view of a mattress cover assembly of the present invention in accordance with another alternative embodiment of the mattress cover assembly, showing a top cover of the mattress cover assembly detached from a bottom cover of the mattress cover assembly, and further showing a blue top panel on the bottom cover of the mattress cover assembly.

(Continued)

The broken lines shown in the drawings are included for purpose of illustrating unclaimed boundary and unclaimed portions of the mattress cover assembly and form no part of the claimed design.

1 Claim, 7 Drawing Sheets
